CAR TRUCK

Robert B. Cottrell, Chicago, Ill., assignor to American Steel Foundries, Chicago, Ill., a corporation of New Jersey

Application February 13, 1941, Serial No. 378,719

16 Claims. (Cl. 105—182)

My invention relates to a railway car truck and especially to a novel form of four wheel railway freight car truck wherein each side frame structure comprises a composite assembly of a beam member and a truss type member, said truss type member affording a central support for the transverse load carrying member or bolster, and wherein a composite spring group is arranged at each corner of the truck through which the truss type side frame member is supported on the beam type member.

An object of my invention is to devise a four wheel railway car truck of novel form wherein the spring suspensions are located adjacent the four corners of the truck instead of, as is more common, adjacent the transverse center line thereof.

My novel car truck contemplates a side frame arrangement including a lower beam-like element with integrally formed journal boxes and spring pockets adjacent the boxes as well as a truss type side frame element on which the bolster or load carrying member may be supported, and wherein said truss type member may be supported in part adjacent the four corners of the truck upon springs seated in said pockets and supported in part on an additional spring of different character, one end of which may seat upon the adjacent journal box and the other end of which may be afforded a seat at a spaced point in said truss member.

More specifically, my novel side frame arrangement contemplates a beam side frame member with integral journal boxes and coil springs positioned on said beam member adjacent each journal box with a truss type side frame element having its ends seated on said springs adjacent said boxes and affording over said coil springs seats for semi-elliptic springs, the outer ends of which may be seated on the adjacent journal boxes and the inner ends of which may be positioned in said truss member adjacent the bolster which is seated therein at the transverse center line of the truck.

In one embodiment shown, I have illustrated my novel beam type side frame member as of box-section which may conveniently be received within the superposed U-section tension member of the truss type side frame element, while in another embodiment, I have illustrated the beam member as of U-section and the tension member of the truss portion as a box-section receivable within the U-section beam member. Application of either of these arrangements in practical struc-

tures will depend upon the particular requirements to be met in each case.

As illustrated,

Figure 1 is a side elevation of a railway car truck embodying my invention.

Figure 2 is a fragmentary top plan view of the truck structure shown in Figure 1.

Figure 3 is a sectional view through the truck structure shown in Figures 1 and 2 taken in a vertical plane bisecting the truck transversely substantially as indicated by the line 3—3 of Figure 1.

Figure 4 is a fragmentary sectional view corresponding in general to the view of Figure 3 but showing a modified form of section for the side frame members.

In my novel truck, each side frame is a built-up structure comprising a bottom beam member generally designated 2 of U-section (Figure 3) comprising the bottom web 4 with upstanding inboard and outboard flanges 6 and 8, and at opposite ends of the beam member 2 are the integrally formed journal boxes 10, 10 forming the usual means of connection to spaced wheel and axle assemblies 12, 12. Adjacent each journal box the inboard and outboard vertical flanges 6 and 8 of the beam member are increased to a depth corresponding substantially to the depth of the journal box, said inboard and outboard deepened flange portions being indicated respectively 14 and 16 and forming the side walls of a spring pocket adjacent each journal box, the bottom of said pocket or spring seat 18 being defined by the web 4 of said beam member. The top wall of each journal box may be inwardly extended as at 20 to merge with the downturned web 22 which affords abutment as at 24 for the end of the truss side frame member generally designated 26, and each end of the truss member 26 may seat as at 28 upon the spring group diagrammatically indicated at 30, said spring group being positioned on the beforementioned spring seat 18. The margins of the spring seat 18 may be defined by transverse flanges 32 and 34 upstanding from the bottom web 4.

As already indicated, the top side frame member 26 is a truss structure including the compression member 36 and the tension member 38 merging with integral spaced columns 40, 40 to form a central bolster opening 42 and the spaced window openings 44, 44, said tension and compression members merging at the extremities of said truss member to form box-sections open at the ends. The upper portion of the bolster opening is relatively wide to accommodate the laterally pro-

jecting inboard and outboard vertical guide lugs 46 and 48 on the bolster 49, said lugs, when said bolster is seated in normal position in the relatively narrow portion at the bottom of the bolster opening, having engagement with the columns, said lower portions of the columns being afforded bolster guide surfaces for engagement with the side walls of the bolster as indicated at 50, 50. The bottom wall of the bolster end is slightly convex longitudinally of the truck as best seen at 52 (Figure 1) in order to permit slight rocking thereof with respect to the tension member 38 on which it is seated as at 54, and the bottom wall of said bolster end is formed with downwardly projecting inboard and outboard horizontal guide flanges 56 and 58 which may abut the inboard and outboard edges of the tension member 38. The tension member beneath said bolster opening may be formed as a box-section with a top web 60, a bottom web 62, and inboard and outboard walls 64 and 66, said box-section being sufficiently narrow to permit vertical movement thereof between the upstanding flanges 6 and 8 of the lower side frame member 2. The bolster 49 is a structure in usual form of box-section comprising the center bearing 68 and spaced side bearings 70, 70 and, in the embodiment shown, has side walls cored away as at 72 to accommodate the passage of brake rods.

Adjacent each column and on the inboard face of each truss member may be formed the usual brake hanger brackets 74, 74, and within each column may be formed a horizontal web 76 with an arcuate top surface 78 defining a spring seat for one end of the semi-elliptic spring 80 which extends through the open end of the box-section end portion and is afforded a seat at its opposite end atop the journal box as at 82. The semi-elliptic spring 80 may be further positioned with respect to the truss side frame member 26 by the seat afforded thereon at 84 for the spring band 86, said spring 80 thereby affording additional support for the end of the truss member 26 which, as already described, is also supported at 28 from coil springs 30. Chafing surfaces or guide surfaces are formed on the inner opposite faces of the flanges 14 and 16 as at 88 and 90 for engagement with the guide surfaces or chafing surfaces 92 and 94 formed on the inboard and outboard walls of the truss member 26 at the extremities thereof.

The modification illustrated in Figure 4 differs from that already described in that the beam side frame member 102 is of relatively narrow box-section so that it may be received between the downturned inboard and outboard flanges 104 and 106 of the inverted U-section tension member generally designated 108 of the truss side frame member which is otherwise similar to the structure of the previous modification. In the modification now under consideration, the top web 110 of the tension member 108 affords a seat as at 112 for the bolster 114 which is formed with inboard and outboard vertical guide lugs 116 and 118 for engagement with the columns 120 as well as horizontal inboard and outboard guide lugs 122 and 124 for engagement with the inboard and outboard faces of the tension member 108. In this modification, likewise, may be formed the usual brake hanger bracket 126 merging with the compression member 128 at its juncture with the column 120. As shown in Figure 4, the box-section beam member 102 may be received between the side flanges of the tension member 108 when normal

relative vertical movement occurs therebetween.

It is to be understood that I do not wish to be limited by the exact embodiments of the device shown which are merely by way of illustration and not limitation as various and other forms of the device will, of course, be apparent to those skilled in the art without departing from the spirit of the invention or the scope of the claims.

10 I claim:

1. In a railway car truck, a composite side frame comprising a U-section beam element with integral journal boxes at the ends thereof and spring seats adjacent said boxes, coil springs on said seats, a truss side frame element superposed on said beam element and including a tension member, a compression member, and spaced columns defining a bolster opening, said tension member being receivable between the spaced webs of said U-section and said tension and compression members merging in box-sections at the ends of said truss element, a bolster extending into said bolster opening with vertical and horizontal guide lugs engaging said columns and said tension member respectively, said truss element having its ends supported on said coil springs and additionally supported on semi-elliptic springs, said semi-elliptic springs having their opposite ends positioned on said boxes, their adjacent ends seated in said columns, intermediate points affording support for the ends of said truss element, and inboard and outboard flanges on said beam element adjacent said boxes affording guide means for the extremities of said truss element.

2. In a railway car truck, a composite side frame comprising a U-section beam element with integral journal boxes at the ends thereof and spring seats adjacent said boxes, coil springs on said seats, a truss side frame element superposed on said beam element and including a tension member, a compression member, and spaced columns defining a bolster opening, said tension member being receivable between the spaced webs of said U-section and said tension and compression members merging in box-sections at the ends of said truss element, a bolster extending into said bolster opening with vertical and horizontal guide lugs engaging said columns and said tension member respectively, said truss element having its ends supported on said coil springs and additionally supported on semi-elliptic springs, said semi-elliptic springs having their opposite ends positioned on said boxes, their adjacent ends seated in said columns, and intermediate points affording support for the ends of said truss element.

3. A composite side frame structure for a railway car truck comprising a lower beam portion with integral journal boxes at the ends thereof and spring seats adjacent said boxes, coil springs on said seats, and a truss portion superposed on said beam portion with its extremities seated on said coil springs, said truss portion comprising tension and compression members and spaced columns defining a bolster opening, spring seats in said columns, springs of different character having their opposite ends seated on said boxes, their adjacent ends seated in said columns and intermediate points affording additional support for the extremities of said truss portion, each journal box having a wall extended to merge with a transverse web forming an abutment for one end of said truss portion to limit relative longitudinal movement between said truss portion and said

beam portion, and means on said beam portion adjacent said abutments affording guide means for the ends of said truss portion.

4. A composite side frame structure for a railway car truck comprising a lower beam portion with integral journal boxes at the ends thereof and spring seats adjacent said boxes, coil springs on said seats, and a truss portion superposed on said beam portion with its extremities seated on said coil springs, said truss portion comprising tension and compression members and spaced columns defining a bolster opening, spring seats in said columns, springs of different character having their opposite ends seated on said boxes and their adjacent ends seated in said columns, and intermediate points affording additional support for the extremities of said truss portion, each journal box having a top wall extended to merge with a transverse vertical web forming an abutment for one end of said truss portion to limit relative longitudinal movement between said truss portion and said beam portion.

5. In a four wheel railway car truck, a composite side frame comprising a beam element with integral journal boxes and spring seats adjacent said boxes, a truss element comprising a compression member, a tension member, and spaced columns forming a bolster opening, a bolster end seated on said tension member in said opening, springs on said spring seats affording support for the ends of said truss element, springs of different types having their opposite ends seated on said journal boxes, their adjacent ends seated in said columns, and affording additional spring support for said truss element, and inboard and outboard flanges on said beam element adjacent said boxes affording guide means for the extremities of said truss element.

6. In a side frame for a railway car truck, a lower element with journal means at the ends thereof, an upper element, resilient means supported from said lower element adjacent respective journal means and affording support for said upper element, and a pair of leaf spring assemblies spaced longitudinally of the frame, said assemblies being supported at the ends thereof adjacent each other from spring seats associated with said upper element and said assemblies being supported at the ends thereof remote from each other from respective journal means, each of said assemblies affording support intermediate the ends thereof for one end of said upper element.

7. In a composite side frame structure, a beam member having journal boxes, inboard and outboard flanges adjacent said boxes defining spring pockets, coil springs in said pockets, a superposed truss element with box-section ends seated on said coil springs, spaced spring seats in said truss element, and semi-elliptic springs having their opposite ends seated on said boxes and their adjacent ends engaging said spaced seats in said truss element and affording additional support therefor, said inboard and outboard flanges affording guide surfaces for the extremities of said truss element.

8. In a composite side frame structure, a beam member having journal boxes, inboard and outboard flanges adjacent said boxes defining spring pockets, coil springs in said pockets, a superposed truss element with box-section ends seated on said coil springs, spaced spring seats in said truss element, and semi-elliptic springs having their opposite ends seated on said boxes and their

adjacent ends engaging said spaced seats in said truss element and affording additional support therefor, certain walls of said journal boxes being extended to form abutment means for the ends of said truss element.

9. A composite side frame structure for a railway car truck comprising a lower beam portion with integral journal boxes at the ends thereof and spring seats adjacent said boxes, coil springs on said seats, and a truss portion superposed on said beam portion with its extremities seated on said coil springs, said truss portion comprising tension and compression members and spaced columns defining a bolster opening, spring seats in said columns, springs of different character having their opposite ends seated on said boxes and their adjacent ends seated in said columns, and intermediate points affording additional support for the extremities of said truss portion.

10. In a four wheel railway car truck, a composite side frame comprising a beam element with integral journal boxes and spring seats adjacent said boxes, a truss element comprising a compression member, a tension member, and spaced columns forming a bolster opening, a bolster end seated on said tension member in said opening, springs on said spring seats affording support for the ends of said truss element, and springs of different type having their opposite ends seated on said journal boxes, their adjacent ends seated in said columns, and affording additional spring support for said truss element.

11. In a side frame structure for a railway car truck, a beam having journal boxes at the ends thereof and flanges defining spring seats adjacent said boxes, springs on said seats, a truss having open ends seated on said springs, spaced spring seats in said truss, and semi-elliptic springs at opposite ends of said side frame structure engaging said spaced seats respectively at their adjacent ends and having their remote ends seated on said boxes, said flanges affording guides for the ends of said truss, certain walls of said boxes being extended to form abutments for the ends of said truss.

12. In a side frame structure for a railway car truck, a beam having journal boxes at the ends thereof and spring seats adjacent said boxes, springs on said seats, a truss having box-section ends seated on said springs, spaced spring seats in said truss, and semi-elliptic springs at opposite ends of said side frame structure engaging said spaced seats respectively at their adjacent ends and having their remote ends seated on said boxes, flanges on said beam affording inboard and outboard guides for the ends of said truss, and abutment means on said beam for said box-section ends.

13. In a side frame for a railway car truck, a lower element with journal boxes and spring seats adjacent thereto, resilient means on said seats, an upper truss element comprising spaced columns defining a bolster opening, said upper element being seated on said resilient means, and semi-elliptic springs seated at their opposite ends on respective boxes and seated at their adjacent ends in respective columns and affording additional support for the ends of said truss element.

14. In a side frame structure for a railway car truck, a beam having journal boxes at the ends thereof, spring seats adjacent said boxes, springs on said seats, a member having ends seated on said springs, spaced spring seats in

said member, and semi-elliptic springs at opposite ends of said side frame structure engaging said spaced seats respectively at their adjacent ends, having their remote ends seated on respective boxes and affording support intermediate their ends for said member.

15. A composite side frame comprising a lower beam element with integral journal boxes and spring seats adjacent said boxes, coil springs on said seats, a truss element superposed on said coil springs with spaced columns forming a bolster opening, spring seats in said columns, and semi-elliptic springs having their opposite ends seated on said boxes and their adjacent ends

seated on said last-mentioned seats and affording additional support for the extremities of said truss element.

16. In a side frame structure for a railway car truck, a beam having journal means at the ends thereof, and spring seats adjacent said means, springs on said seats, a truss having ends seated on said springs, spaced spring seats in said truss, and semi-elliptic springs affording additional support for said truss and engaging said spaced seats respectively at their adjacent ends and having their remote ends seated on said means.

ROBERT B. COTTRELL.
